UNITED STATES PATENT OFFICE.

LUTHER K. JEWETT, OF BOSTON, MASSACHUSETTS.

CAR-TRUCK.

SPECIFICATION forming part of Letters Patent No. 402,163, dated April 30, 1889.

Application filed October 12, 1888. Serial No. 287,924. (No model.)

To all whom it may concern:

Be it known that I, LUTHER K. JEWETT, of Boston, county of Suffolk, State of Massachusetts, have invented an Improvement in Car-
5 Trucks, of which the following description, in connection with the accompanying drawings, is a specification, like letters on the drawings representing like parts.

This invention relates to car-trucks of that class in which a metallic bolster is fitted into and vertically movable in a metallic transom, and is an improvement upon the car-truck shown and described in another application, Serial No. 251,705, filed by me October 7, 1887.
10 One feature of my present invention consists in constructing the metallic transom as will be described, whereby it is strengthened at its upper part to enable it to withstand excessive strain and prevent it being bent
15 or doubled by shocks, such as would arise in suddenly starting and stopping the car.

My improved transom also affords a support for the saddle-bar when carried in toward the center of the truck, as when elliptical springs are used to support the bolster. The transom is also constructed to permit of the passage of air through it, thereby lessening resistance when the car is moving at a high rate of speed. The peculiar construction
20 of the transom permits water and dirt to pass off freely.

Another feature of my invention consists in supporting the end curve-plates upon the transom, so that when rounding curves the car is maintained substantially level, as will
25 be described.

Still another feature of my invention consists in making the bolster of preferably metallic tubes, by which increased strength, 30 coupled with lightness and simplicity of construction, is obtained.

The tubes referred to are supported by bolster-sustaining blocks, preferably made in one piece or casting, but which may be made in two parts suitably bolted or riveted together. The bolster-sustaining blocks are preferably provided with chafe-irons, to obviate wear upon the bolster.
45

My invention further consists in making

the upper or top side of the arch-bar-sustaining blocks concaved downward, and forming or shaping the arch-bar to conform to it, for a purpose as will be described.

Still another feature of my invention consists in a novel pedestal-strap, to be herein-
55 after described.

The particular features in which my invention consists will be pointed out in the claims at the end of this specification.

Figure 1 is a side elevation of a car-truck 60 embodying my invention; Fig. 2, a partial end elevation and transverse section of the car-truck shown in Fig. 1, the section being taken on line $x_1 x_1$; Fig. 3, a top or plan view of the truck shown in Fig. 1. Fig. 4 is a side eleva- 65 tion and longitudinal section of the transom, showing part of one arch-bar-sustaining block in section, the section being taken on line $y_1 y_1$; Fig. 5, a top or plan view of the transom partially broken out; Fig. 6, a section 70 of the transom in the line $x_2 x_2$; Fig. 7, a partial longitudinal section and elevation of a bolster and its sustaining-blocks; Fig. 8, a partial top view of the bolster and its sus- 75 taining-blocks shown in Fig. 7; Fig. 9, a sec-
tion in line $x_3 x_3$ of the bolster and its sustain-
ing-blocks shown in Fig. 8; Fig. 10, a section
through the center of the bolster in the line
 $x_4 x_4$; Figs. 11 and 12, details to be re-
ferred to, Fig. 12 being a top or plan view of 80
Fig. 11; Fig. 13, a top or plan view of the saddle; Fig. 14, a section in line $x_5 x_5$ of the saddle
shown in Fig. 13; Fig. 15, a detail of the rocker;
Fig. 16, a top view of the end curve-plate;
Fig. 17, an end elevation of the curve-plate 85
shown in Fig. 16, and Fig. 18 a side elevation
of the end curve-plate.

Referring to Figs. 1 and 6, the transom is composed, as shown, of two side pieces, a , corner pieces, a' , and bottom pieces, a'' , prefer- 90 ably of steel, which are riveted, as herein shown, to inside castings or braces, a^3 . The side pieces, a , and corner pieces, a' , are riveted to the arch-bar-sustaining blocks a^4 , each side piece, a , abutting against and being sup- 95 ported by shoulders a^5 , (see Fig. 6,) and the corner pieces abutting against shoulders a^6 of the arch-bar-sustaining blocks a^4 . The tran-

5 som is open between the side pieces and corner pieces, so that air is permitted to pass readily through the transom when the truck is in motion, and the said transom being open at its bottom between the piece a^2 and corner pieces permits water and dirt to pass through the transom. The side pieces, a , are made of suitable thickness to stiffen the upper part of the transom and enable it to withstand shocks such as due to suddenly starting and stopping the car with which the truck is used.

10 The transom at its ends supports, as shown, a frame, b , sustaining end curve-plates, (not herein shown,) but which will preferably be substantially such as shown and described in the application referred to, the curve-plate-supporting frame serving as a stop to limit the side swaying or tipping of the car when 15 rounding a curve, or when the car is running on irregular tracks, thereby maintaining a substantially horizontal position and effecting a more even riding of the car.

20 The transom receives within it the bolster composed, preferably, of two or more metallic tubes, b' , the said tubes, as herein shown, being supported by sustaining-blocks b^2 , each of which is preferably cast in one piece, but which may be preferably made in two parts 25 secured together, as by rivets or bolts. The bolster-sustaining blocks b^2 are provided, as herein shown, with chafe-irons b^4 , which co-operate with the upper portion of the castings or transom-braces a^3 , which are preferably widened, as at b^5 . (See Fig. 4.)

30 Instead of providing the bolster-sustaining blocks b^2 with chafe-irons, the bolster-tubes may have chafe-irons b^4 riveted or otherwise secured to them, as shown in Figs. 11 and 12.

35 40 The tubular bolster is supported within the transom, as herein shown, by elliptical springs b^6 , resting on a spring-seat, b^7 , which is itself rocked upon the hanger-seat b^8 , (see Fig. 2,) the said hanger-seat being sustained at each 45 end by a hanger-link, b^9 , passed over the rocker-bar b^{10} , substantially as in the application referred to. The rocker-bar b^{10} is mounted upon a saddle, c , (see Figs. 13 and 14,) and the said saddle is supported directly upon the 50 side pieces, a , of the transom, and the upper arch-bar, c' , and its sustaining-blocks a^4 , the saddle-bar being secured by suitable bolts c^5 , which are extended through the saddle-bar, arch-bar-sustaining blocks, and pedestal-strap 55 c^6 , as shown in Fig. 1, to securely unite or tie the said parts together. Each arch-bar sustaining block a^4 is cast with its upper or top side, 2, (see Fig. 1,) concaved downward, and the upper arch-bar, c' , is bent or shaped to 60 conform to the shape of the casting. This construction prevents the upward buckling of the upper arch-bar when the truck is abnormally loaded, because the said arch-bar to buckle would have to elongate, and it is prevented from so doing by the truss c^7 , which

65 supports the transom and encircles the ends of the upper arch-bar. To permit the upper arch-bar to buckle the truss c^7 would have to be elongated, which is substantially impossible. The pedestal-strap c^6 , connecting the pedestals and transom for sake of stiffness or rigidity, is composed of a single bar corrugated, preferably, on both sides, as shown in Fig. 2.

70 My improved truck will preferably be provided with the equalizer-bar d and equalizer-springs d' , substantially as shown in the application referred to.

I claim—

1. In a car-truck, the combination, with a metallic transom composed of independent pieces of castings or braces to unite the said pieces to form the transom, of sustaining-blocks provided with shoulders to co-operate with the said pieces, substantially as described.

2. In a car-truck, a metallic transom composed of independent side and corner pieces, combined with sustaining-blocks provided with shoulders to co-operate with the said pieces, and with braces or castings to unite the said pieces to form the transom, substantially as described.

3. In a car-truck, the combination, with a metallic transom, of a curve-plate-sustaining frame secured at or near the ends of the said transom, substantially as described.

4. In a car-truck, the combination, with a transom, of a bolster vertically movable therein and composed of independent tubes, and sustaining-blocks for said tubes, substantially as described.

5. In a car-truck, the combination, with a transom composed of independent pieces, of a bolster vertically movable therein and composed of tubes, and sustaining-blocks for said tubes, substantially as described.

6. In a car-truck, the combination, with a transom composed of independent pieces, and castings or braces to unite said pieces together, of a bolster composed of independent tubes and vertically movable in said transom, sustaining-blocks for said tubes, and chafe-irons to prevent wear of the bolster-tubes, substantially as described.

7. In a car-truck, the combination, with a transom composed of independent pieces, and castings or braces to unite said pieces together, of a bolster composed of tubes and vertically movable in said transom, sustaining-blocks for said tubes, and chafe-irons secured to said bolster-sustaining blocks, substantially as described.

8. In a car-truck, the combination, with a transom, of arch-bar-sustaining blocks having their upper or top sides concaved downward, and arch-bars shaped or bent to fit said concaved sides, as and for the purpose specified.

9. In a car-truck, the pedestal-strap com-

posed of a single corrugated bar, substantially as described.

10. In a car-truck, the combination, with an arch-bar-sustaining block, of a metallic transom having its upper end resting upon and supported by the top of the said sustaining-block, substantially as described.

In testimony whereof I have signed my name to this specification in the presence of two subscribing witnesses.

LUTHER K. JEWETT.
